UNITED STATES PATENT OFFICE.

ANDREW J. JOHNSON, OF CLEVELAND, OHIO.

BURNER.

1,231,369.

Specification of Letters Patent. Patented June 26, 1917.

Application filed July 17, 1912. Serial No. 769,914.

To all whom it may concern:

Be it known that I, ANDREW J. JOHNSON, a citizen of the United States, residing at Cleveland, in the county of Cuyahoga and 5 State of Ohio, have invented certain new and useful Improvements in Burners, of which the following is a specification.

This invention relates to improvements in heating devices for printing presses and relates particularly to certain mechanism for confining the open flame and the heat therefrom directly to the underside of the printed sheet and to certain other details relating to the delivery of the sheet to the burner 15 and in the adjustment of the guards used in conjunction with the burner.

The invention may be further briefly summarized as consisting in the combination and construction of parts hereinafter set forth 20 in the following description, drawings and claims.

Referring to the drawings, Figure 1 is a side elevation of a portion of the delivery tapes of the press showing the burner in 25 its relation thereto; Fig. 2 is a top plan view of the burner mechanism; Fig. 3 is a longitudinal section through the mixer; Fig. 4 is a transverse section on the line 4—4 of Fig. 2; Fig. 5 is a section upon the line 30 5—5 of Fig. 2 and Figs. 6 and 7 are detail views.

In carrying out the invention any preferred form and construction of parts may be employed so long as they possess the 35 necessary characteristics, but I have shown the invention applied to the delivery mechanism of a press, wherein 1 represents one of the wheels which carries the usual tape 2. This delivery mechanism comprises a 40 plurality of narrow belts which convey the printed sheet from the press onto a suitable receiving board or table and the device covered by this application is applied as near as practical to the end of these belts and 45 is adjacent to their supporting rollers 1.

Secured to a bar 3, which forms a part 50 of the press, or in any other suitable manner, is a split collar 4 having secured thereto by means of a bolt 5 an ear 6 forming a part of a sleeve support 7. There is one of these complete devices at each side of the machine and they carry a main burner tube 8 rigidly held in these sleeves by suitable set screws 9. This burner tube 8 is closed at 55 one end and is provided throughout its length with a plurality of gas orifices 10

arranged in a line longitudinally of the tube. The tube may be adjusted and held by the set screws 9 in a position so that they are near the top of the burner tube, as shown 60 in Fig. 5. One end of this tube is provided with a suitable opening 11 for receiving air to form a mixture, and telescoping about this tube is a split sleeve 12 which fits the tube snugly and serves as a means for adjusting the volume of air admitted. Fitting in the end of the tube is a gas connection 13 provided with a gas nozzle 14 arranged to project a stream of gas into the burner tube 8. This gas connection is held 70 in place by a pressure created by a set screw adjacent this end of the burner.

The operation of the burner itself is similar in all respects to that which takes place in ordinary burners, and the invention resides in certain guards and attachments in 75 connection with this burner, as will be brought out.

Secured to the burner, preferably toward the underside and away from the feeding belts, are suitable brackets 15 each provided with a slot 16 for receiving a screw 17 threaded into the burner tube and adapted to clamp down against a washer 18 to hold the brackets in place, the slot serving to permit adjustment of these brackets around the tube. Each bracket is provided with an outwardly extending plate portion 19 having a slot 20 for receiving a screw 21 which passes through a confining guard plate 22 into a suitable nut 23 on the bottom of the plate portion 19. This confining plate is adjusted so that it extends out in a direction such that it will touch the underside of the printed sheet as it passes from the press, and for a purpose to be later described. The plate is preferably cut with V-shaped 90 openings 24 at various points throughout its length to permit of expansion of the portions between these cuts as the plate becomes 95 heated from the flame.

Secured to the upper part of the burner tube and extending throughout its length is a guard plate 25 which extends out over the burner orifices but does not extend far enough to prevent the flames themselves from engaging the underside of the printed sheet. This guard is held in place by means of a strip 26 secured to the burner tube by means of screws 27 passing through openings in the strip 26 and the guard plate 25 and threaded into the burner tube. This 105 110

strip 26 also serves to hold the shanks 28 of suitable guides 29 in place. These guides 29 extend to the rear and toward the feeding belts to bridge the gap and prevent the 5 paper from passing down between the burner and the feeding mechanism.

In order to adjust the effective length of the burner it may be provided with guides 30 secured to the burner tube 8 on either 10 side of the burner orifices and serving to guide a plate 31 arranged to slide over the orifices and close more or less of them as desired.

In use, the operator adjusts the amount 15 of gas in the mixer so that he obtains a blue flame throughout the length of the burner and further so that the flames extend beyond the edge of the guard plate 25 and also adjusts the outer edge of the confining plate, so that 20 it will touch the underside of the printed sheet. During the operation of the press the paper passes over the burner and the flames together with the heat confined in the space between the confining plate and 25 the guard plate causes the sheet to be heated and the ink to be dried sufficiently to prevent offsetting.

Having described my invention, I claim:—

1. Burner mechanism for printing presses 30 comprising a burner supported at a point near the path of the paper in its delivery from the press, and means for confining the heat from the flame of the burner against the under side of the sheet.

35 2. Burner mechanism for printing presses comprising a burner supported at a point near the path of the paper in its delivery from the press, and a device carried by the burner and extending to a point coincident 40 with the path of the paper for confining the heat of the flame of the burner against the under side of the sheet.

45 3. Burner mechanism for printing presses comprising a burner supported at a point near the path of the paper in its delivery

from the press, and a confining plate carried by the burner and extending to a point coincident with the path of the paper.

4. Burner mechanism for printing presses comprising a burner supported at a point 50 near the path of the paper in its delivery from the press, brackets carried by the burner, and a confining plate supported on the brackets and extending to a point coincident with the path of the paper in its 55 delivery from the press and adapted to confine the heat from the flame of the burner against the under side of the sheet.

5. Burner mechanism for printing presses comprising a burner supported at a point 60 near the path of the paper in its delivery from the press, brackets carried by the burner, and a confining plate supported on the brackets extending to a point coincident with the path of the paper and provided 65 with cut off portions to permit the expansion of the confining plate.

6. Burner mechanism for printing presses comprising a burner supported at a point 70 near the path of the paper in its delivery from the press, brackets carried by said burner, a confining plate supported upon said brackets extending from the burner to a point coincident with the path of the paper in its delivery, and a guard plate extending from the top of the burner over a 75 portion of the flame.

7. Burner mechanism for printing presses comprising a burner, a strip secured to said burner and extending the length thereof, 80 and removable guides having portions engaging under said strip, said guides being adapted to project into the space between the burner and the delivery mechanism.

In testimony whereof I affix my signature 85 in presence of two witnesses as follows.

ANDREW J. JOHNSON.
